 a corporation of Delaware

Application May 11, 1950, Serial No. 9,859

Term of patent 14 years

(Cl. D48—2)

To all whom it may concern:

Be it known that I, Norbert J. Baumer, a citizen of the United States of America, residing at East Orange, in the county of Essex, in the State of New Jersey, have invented a new, original, and ornamental Design for a Candleholder of which the following is a specification, reference being had to the accompanying drawings, forming a part thereof.

Fig. 1 is a view in side elevation of a candleholder, showing my new design,

Fig. 2 is an exploded view in side elevation thereof, and

Fig. 3 is a top plan view.

The dominant features of my design are shown in full lines in Fig. 1 of the drawing.

I claim:

The ornamental design for a candleholder, substantially as shown and described.

NORBERT J. BAUMER.
